Schiffmiller & Pieroni, P.C.(57) **CLAIM**

The ornamental design for a jewelry component, as shown and described.

DESCRIPTION

FIG. 1 is a perspective view of a jewelry component according to my new design.

FIG. 2 is a top plan view thereof.

FIG. 3 is a front elevational view thereof, the rear elevational view being a mirror image thereof.

FIG. 4 is a right side elevational view thereof, the left side elevational view being a mirror image thereof; and,

FIG. 5 is a bottom plan view thereof.

The broken lines shown in the drawings illustrate environmental structure and form no part of the claimed design.
